DRAFT RIGGING

Donald S. Barrows, Rochester, N. Y., assignor to
The Symington Company, New York, N. Y., a
corporation of Maryland

Application October 2, 1929, Serial No. 396,758

15 Claims. (Cl. 213—69)

This invention relates to draft rigging for railway rolling stock and, more particularly, to mechanism for operatively connecting the coupler and yoke while allowing the desired amount of angling therebetween in all directions.

The principal object of my invention, generally considered, is to provide a universal connection between the coupler and yoke members of railway draft rigging.

Another object of my invention is to provide a connection between the coupler and yoke of railway draft rigging with the allowance of substantially universal motion therebetween by forming interengaging substantially spherical surfaces on the associated members.

A further object of my invention is to provide a key connected coupler and yoke with a block mounted on the key and provided with substantially spherical portions which fit into and serve as a bearing for the butt of the coupler stem which surrounds and engages the block, an auxiliary member being provided embracing the coupler stem and presenting a substantially spherical pocket which serves as a bearing for a similarly shaped butt portion on the coupler, the key serving to connect the coupler, through the block therein, to the auxiliary member and the associated yoke, whereby draft forces therebetween are transmitted by the key, and buffing forces by the auxiliary member, to an associated front follower and/or cushioning mechanism.

Other objects and advantages of the invention relating to the particular arrangement and construction of the various parts will become apparent as the description proceeds.

Referring to the drawing illustrating my invention, the scope whereof is defined by the appended claims.

Figure 1 is a top plan, partially in horizontal section, illustrating a coupler and yoke connection embodying my invention.

Figure 2 is a side elevation partly in vertical longitudinal section of the construction shown in Figure 1.

Referring to the drawing in detail, like parts being designated by like reference characters, there is shown a coupler, the stem 1 of which is connected to a yoke 2 by means of a transversely extending key 3. The coupler stem is formed

50 with a butt portion, the outer surface 4 of the rear wall 5 thereof being formed substantially spherical and adapted to bear against a transverse portion 6 of an auxiliary member 7 having forwardly extending walls or arms 8 embracing

5 slotted for receiving the key 3. The transverse portion 6 of the auxiliary member or swivel block 7 is shown as integral with the forwardly extending arms 8 and the front face 9 thereof is concave, substantially spherical and preferably accurately fits the rear surface 4 of the coupler butt so that angling or substantially universal movement between said coupler and auxiliary member, as well as the associated yoke, is permitted. The rear portion of the yoke 2 (not shown) may be of usual construction.

10 The butt portion of the coupler stem 1 is formed with a pocket 10 into which is fitted a block 11. The pocket 10 is formed between upper and lower walls 12 and 13 respectively of the coupler, which walls are normally horizontal, and the rearward and forward walls 5 and 14, respectively, of said coupler butt, said latter walls preferably having concave substantially spherical inner surfaces 15 and 16, respectively. These inner surfaces are preferably substantially concentric with the spherical surfaces 4 and 8 on the coupler butt 1 and auxiliary member 7, respectively. The block 11 fitting in the coupler pocket 10 is preferably formed with upper and lower flat surfaces 17 and 18, respectively, and rearward and forward convex substantially spherical surfaces 19 and 20, respectively. The flat surfaces 17 and 18 on the block 11 are preferably spaced from the cooperating upper and lower walls of the coupler pocket to permit the desired amount of play or motion therebetween, whereas the spherical surfaces 19 and 20 on the block are embraced between the complementary spherical surfaces 15 and 16 of the pocket with preferably only a slight amount of play therebetween. As the spherical surfaces on the block are substantially concentric with the complementary surfaces on the pocket, a desired amount of angling or pivotal motion between the coupler and block is permitted in all directions.

15 The block 11 is provided with a transverse slot 21 through which normally extends the key 3 for connecting the coupler, block, auxiliary member, and yoke. The arms of the yoke are correspondingly slotted, as indicated at 22. It will be seen by inspection of Figure 1 that draft forces are transmitted from the coupler to the yoke through the block 11 and key 3, the coupler being allowed to angle or swivel about the block 11. Buffing forces, however, are preferably transmitted directly from the rear surface 4 of the coupler stem 1 to the auxiliary member 7 and from there to an associated follower 23 and/or cushioning mechanism (not shown). If a fol-

lower 23 is employed between the arms of a horizontal yoke 2, said follower is desirably held in place by means of a second key 24 passing through a slot 25 in the follower and slots 26 in the arms of the yoke.

In order to assemble the block 11 in the pocket 10 of the coupler stem, it is necessary to turn the same from the position shown in Figure 1 through substantially 90° in a horizontal plane. 10 It will then be possible, because of the relative width and length of the block, to move it transversely into position between the front and rear walls defining the pocket 10, whereupon the block is then turned back through approximately 15 90° so that the convex spherical surfaces thereon will engage with the complementary surfaces on the interior of the pocket. When the parts are assembled, the clearances are preferably such that engagement is effected between the convex 20 butt of the coupler and the corresponding surfaces on the auxiliary member 1 before the concave surface 16 on the coupler stem engages the convex surface 20 on the block 11, whereby buffering forces are directly transmitted from the rear 25 surface of the coupler butt to the auxiliary member rather than from the block 11 through the key 3 to said auxiliary member, although I do not wish to be limited to this showing.

From a consideration of the foregoing disclosure, it will be seen that I have provided a connection between a coupler and yoke for railway draft rigging which allows for universal angling therebetween to a desired extent. Although a preferred embodiment of my invention has been illustrated, it will be understood that I do not wish to be limited to the details as modifications may be made within the scope of my invention as defined by the appended claims. It will be seen that on account of employing an auxiliary member between the butt of the coupler and the front follower, universal angling is provided for on buff, while at the same time it is possible to use an ordinary or substantially standard front follower supported by a second key.

Having now described my invention, I claim:

1. In railway draft rigging, in combination with a coupler, a main yoke, a key connecting said coupler and yoke, said coupler and key having an element therebetween to provide a universal joint, and an auxiliary member with arms at the sides operatively embracing the stem of said coupler and said element and each arm intersected by said key, to hold the parts assembled to receive buffering forces from the coupler.

2. In railway draft rigging, in combination with a coupler, a main horizontal yoke, a key adapted to transmit draft forces between said coupler and yoke, an auxiliary member mounted on said key and fitting in a pocket in the stem of said coupler to provide for universal movement between said coupler and yoke, and a supplemental member with forwardly extending arms embracing the stem of said coupler and connected thereto by said key for the transmission of buffering forces.

3. In railway draft rigging, in combination with a coupler stem having a substantially spherical butt portion, a yoke, a follower disposed between the forwardly extending arms of said yoke, and an auxiliary member disposed between the butt of said coupler stem and said follower, having a front face of substantially spherical conformation and concentric with the butt portion of the coupler for universal move-

ment therebetween, and forwardly extending arms disposed at the sides of, and in embracing relationship with, the coupler stem, and means extending between said coupler and yoke for transmitting draft forces and individually connecting each of said arms to said coupler.

4. In railway draft rigging, in combination with a coupler stem having a substantially spherical butt portion, a yoke having a cushioning mechanism pocket, a front follower closing the front end of said pocket, and an auxiliary member between said follower and the butt of said coupler stem, with arms embracing said stem, and formed with a substantially spherical pocket fitting the coupler butt for receiving buffering forces therefrom and for universal movement with respect thereto, and means intersecting said coupler, yoke and each of the arms of said auxiliary member for holding the parts assembled.

5. In railway draft rigging, in combination, a coupler having a stem with a cavity therein, walls of which are substantially spherical, a block mounted in said cavity and having surfaces approximately concentric with the curved surfaces of said cavity, a yoke, an auxiliary member with forwardly extending arms lying on either side of and embracing the stem of said coupler and said block for transmitting buffering forces from said coupler, and means extending through said block and the arms of said auxiliary member for connecting the coupler and yoke.

6. In railway draft rigging, in combination, a coupler provided with a pocket in its stem, two opposite walls of said pocket being substantially spherical, means mounted in said pocket and having substantially spherical surfaces fitting the spherical walls of the pocket in the coupler, a yoke, means with side arms embracing the stem of said coupler and embraced by the arms of said yoke for transmitting buffering forces from said coupler, and means extending through said means in said pocket and the side arms of said embracing means for connecting the assembled parts.

7. In railway draft rigging, in combination, a coupler stem having a rear transverse wall and a forwardly spaced transverse wall, the inner faces of said walls being substantially spherical, a slotted block mounted between said walls and having bearing surfaces to fit between the spherical portions of said walls, an auxiliary member with side arms embracing the stem of said coupler and said block for transmitting buffering forces from said coupler, a yoke embracing said auxiliary member, and a key extending through the slot in the block and said yoke and the arms of said auxiliary member for the transmission of draft forces between said coupler and yoke and holding the parts assembled.

8. In railway draft rigging, in combination, a coupler stem having a rear integral transverse wall and an integral transverse wall forwardly spaced with respect thereto, the inner faces of said walls being substantially concentric and spherical, the outer face of the rear wall being curved substantially concentric with the inner face thereof, a slotted block mounted between said walls and having bearing surfaces shaped to fit between the spherical portions thereof, an auxiliary member engaging said coupler stem and formed with forwardly extending arms embracing said block, a horizontal yoke with forwardly extending arms embracing said auxiliary mem-

- ber on either side of the arms thereof, a key extending through slots in the block, and in the arms of said auxiliary member and yoke for connecting the parts, that portion of the auxiliary member adjacent the curved outer face of the rear wall of the coupler stem being correspondingly curved to fit said face and adapted to bear thereon for the transmission of buffing forces.
9. In railway draft rigging, in combination, a coupler provided with a butt substantially spherical on its rear surface, an auxiliary member embracing the butt of said coupler and provided with a portion adjacent the spherical portion thereof fitting said spherical portion, and a key passing through registering slots in said auxiliary member and coupler for connecting said parts, sufficient clearance for the key being provided to permit universal angling of the coupler with respect to said member.
10. 10. In railway draft rigging, in combination, a coupler stem with a butt substantially spherical on its rear surface and having a pocket formed between a rear wall thereof and a forwardly spaced wall, the inner surfaces of said walls being substantially spherical and concentric with the rear surface of the butt, a block mounted in said pocket, a yoke associated with said coupler stem, an auxiliary member disposed between the arms of said yoke and having side arms embracing the butt of said coupler, said auxiliary member having a forward face substantially spherical and fitting the rear surface of the coupler butt, and means connecting said block, each arm of said auxiliary member and said yoke.
- 35 11. In railway draft rigging, in combination, a coupler stem with a butt substantially spherical on its rear surface and having a pocket therein between rear and forwardly spaced walls, the inner surfaces of said walls forming a portion of an approximate sphere substantially concentric with the rear surface of the butt portion, a block mounted in said pocket and fitting between said walls, an auxiliary member with arms embracing the butt of said coupler at the sides thereof and presenting a portion contacting and fitting the spherical butt of the coupler, yoke-acting means with the forward portions lying on opposite sides of said auxiliary member arms and the stem of the coupler, and means extending through said yoke-acting means, each arm of said auxiliary member and said block, for connecting said members.
- 55 12. A coupler provided with a stem having a substantially spherical butt portion and formed with a pocket therein between a rear wall and a wall forwardly spaced therefrom, the inner surfaces of said walls being substantially spherical and concentric with the butt portion, a block mounted in said pocket and formed with curved surfaces fitting the surfaces of the walls of said pocket, an auxiliary member closely embracing the spherical butt portion and formed with a curved surface fitting the spherical butt portion of the coupler, and a key extending through registering slots formed in the auxiliary member and block for holding the parts assembled.
13. A car coupler involving a shank member having a rear end wall and a transversely extending slot in advance thereof, said rear wall having curved rear and forward surfaces, a bearing block having a curved forward face cooperating with said curved rear surface, and a key seat member positioned in said slot and having a curved rear face cooperating with said curved forward surface of said rear wall, the bearing block being provided with forwardly extending arms embracing said shank member and key seat member and serving to connect said block to said key seat member.
14. A car coupler adapted for attachment to a draft yoke or the like, said coupler involving a shank member provided at its rear end with a horizontally and vertically curved exterior surface and having in advance of said surface a vertically and horizontally curved interior face and having a transversely extending slot in advance of said surface, a key seat member having a curved rear face corresponding to and engaging said interior face of the shank member, a bearing block having a flat rear face adapted to engage the follower of a draft gear and having a vertically and horizontally curved forward surface for cooperating with said exterior surface of the shank member, and means attaching said bearing block to the shank member, said means including said key seat member.
15. A car coupler adapted for attachment to a draft yoke or the like, said coupler involving a shank having a rear end wall and a transversely extending slot in advance thereof, said rear wall having a curved rear surface and a curved forward surface, a key seat member having a curved rear face corresponding to and engaging said forward surface of said rear wall, a bearing block member adapted to engage the follower of a draft gear and having a curved forward face for cooperating with said curved rear surface of said rear wall of the shank member, said curved surfaces of the rear wall of the coupler shank being adapted to permit one of said members to angle horizontally with respect to said shank and the other of said members to angle vertically with respect to said shank, and means engaging the key seat member for attaching the bearing block member to said key seat member.

DONALD S. BARROWS.
